TUBE DRAWING MACHINE

John William Lawrence, Leicester, England, assignor to Lawrence Holdings (Overseas) Limited, London, England

Filed May 22, 1953, Ser. No. 356,866

5 Claims. (Cl. 113—34)

This invention relates to tube drawing machines, and has reference particularly to such machines for producing lock seamed tubes for use in the construction of core structures of the finned tube type.

Finned tube core structures are embodied in heat exchange apparatus such, for instance, as radiators for use in conjunction with liquid cooled internal combustion engines, and are alternately known as cores of the "gilled tube" or "fin and tube" type.

A finned tube core structure comprises a plurality of tubes, usually of a flat or oval section, these tubes extending through spaced fins adapted to provide heat dissipating or radiating surfaces.

Conventional methods of producing these tubes require the provision of a large machine including a plurality of pairs of shaped rollers adapted progressively to form the tube in a number of successive stages. The output of such known machines, as well as their capital cost, is very high, and as a consequence their use is confined to large undertakings.

The object of the present invention is to provide a machine of simple construction and low capital cost designed to produce efficient tubes at a rate more suited to the needs of the smaller manufacturer.

The machine constituting this invention essentially includes a die head comprising appropriately contoured fixed die parts or portions between which an initially flat strip of relatively thin and easily deformable metal can be drawn, the said fixed parts or portions being adapted to convert this metal from the flat condition into lock seamed tubing.

Thus, the die head embodies opposed and laterally spaced complementary die parts or portions which are fixed, in contra-distinction to being rotatable as are rollers, but which, like the pairs of rollers in the prior costly machines, are adapted for action upon strip metal suchwise as to form tubing therefrom in progressive stages.

In one convenient embodiment of the invention, the die head incorporates a continuous and unitary fixed die which may advantageously be made by any appropriate one of the modern precision casting methods. Alternatively, what is in effect a continuous fixed die may be built up in sections, or it may even be produced by electro deposition on wax or equivalent patterns or forms.

Moreover, instead of providing in the simplified machine of this invention a continuous die, it is also within the scope of the said invention to employ two or more adjoining or longitudinally spaced fixed dies or die sections each adapted to perform at least one of the progressive stages of the tube drawing process.

As will be appreciated, the fixed die parts or portions may be made readily removable and replaceable by others, according to the cross-sectional shape and dimensions of the tubing to be produced.

The leading section of the die head may conveniently be so contoured as first to fold an initially flat strip of metal into a U formation in section with widely separated

2

limbs, and to reduce the width of the U until the limbs (to constitute the sides of the drawn tubing) are spaced apart only a short distance and parallel to each other, with one of the limbs extending a little beyond the other.

5 The opposed complementary and appropriately contoured parts of the following portion or section of the die head may then act to bend the free edge of the shorter limb first inwards towards and then parallel to the longer limb so as to form a longitudinal flange, next to bend the 10 projecting edge of the longer limb first laterally inwards and then downwards so that it enfolds the aforesaid flange to produce a tube-closing seam, and finally to bend the inter-engaged portions of the two limbs constituting the seam so that they lie against one of the narrow sides of the resulting flat section lock seamed tubing.

The improved and simplified machine of this invention also essentially includes means for gripping and feeding forwards the finished tubing emerging from the die head and so continuously drawing the strip metal through the die or dies. The feeding means may be of any suitable character, although it is preferred to employ for this purpose a pair of appropriately knurled or similarly formed wheels. Alternatively, the feeding means may comprise an endless roller or equivalent chain furnished with pairs of laterally spaced shoes arranged at respectively opposite sides of the tubing issuing from the die head, and relatively stationary parts adapted, during travel of the chains, to cause the pairs of shoes to grip the tubing seriatim and so draw it continuously forwards through the die head.

It is necessary to associate with the die head a mandrel about which the tubing can be formed, this mandrel also serving to prevent the grip of the feeding means from crushing the said tubing.

35 Immediately following the die head there is provided a pair of rollers which are arranged to engage and press upon the narrow sides of the lock seamed tubing for the purpose of squeezing down and flattening the tube-closing seam and bringing the tubing to the correct size.

In order that the invention may be more clearly understood and readily carried into practical effect, a specific constructional example of the new or improved tube drawing machine will now be described with reference to the accompanying drawings, wherein,

45 Figures 1 and 1A are general perspective views of the principal section of the machine showing, inter alia, the die head, the mounting for the rollers arranged to squeeze down and flatten the tube-closing seam, and the knurled feed wheels, the perspective view having been divided along the common dot-dash line of each,

50 Figure 2 is a side view of the rollers for squeezing down and flattening the tube-closing seam,

Figure 3 is a cross-sectional view taken on the line 111—111 of Figure 2,

55 Figure 4 is a more or less diagrammatic representation, in exploded form, showing a length of tubing as it appears at various stages during closing of the same, and also the opposed sets of die plates employed to produce the tube-closing seam,

60 Figures 5 and 6 depict more clearly the operative ends of the die plates of two opposed sets respectively,

Figures 7 and 8 are detail perspective views of the operative ends of two of the said die plates, and

65 Figures 9—12 are detail sectional views illustrating successive stages in the closing of the tubing.

Like parts are designated by similar reference characters throughout the drawings.

Referring to Figure 1A, it will be seen that the die head, indicated generally by the letter A, comprises a leading sheet metal trough 1, a following unit 2 consisting of two blocks 3 and 4 which are arranged side by

side with a distance piece between them suchwise as to provide a longitudinally extending channel 5, and which have clamped to the top surfaces thereof opposed sets of fixed die plates 6—12. The trough 1, a portion only of which is depicted in Figure 1A, is so contoured and formed at the top with inwardly directed flanges 1a as first to fold an initially flat metal, e.g. copper strip such as that indicated at 13 in Figures 9—12 into a U formation in section with widely separated limbs and then to reduce the width of the U until the limbs 13a and 13b are spaced apart only a short distance and are parallel to each other, with the limb 13a extending a little beyond the limb 13b. This intermediate stage in the conversion of the strip metal from the flat condition into lock seamed tubing (of the cross-section shown in Figure 12) occurs immediately prior to the stage illustrated in Figure 9. The trough 1, moreover, is mounted on supporting legs 14 which stand on a drip tray 15 in turn carried by a platform 16 mounted on a bed 17. During the initial folding operation performed by the appropriately contoured trough 1, the strip metal may advantageously be lubricated with oil, in which instance the surplus oil would be collected in the tray 15.

The unit 2, with its opposed sets of fixed die plates 6—12, is also mounted on the platform 16 and functions to close the tubing drawn through the channel 5. Thus, as the folded metal strip 13 issues from the trough 1 the upper end portions of the upstanding limbs 13a and 13b first pass between the operative ends of the pair of opposed die plates 6 and 7. As will be seen from Figures 4, 5, 6 and 9, the operative end of the die plate 6 is wholly flat and disposed in a vertical plane, whereas the opposed end of the die plate 7 is curved and formed at the appropriate top corner thereof with a laterally protruding lip 7a. The end of the plate 6 accordingly has no appreciable effect on the upwardly projecting edge portion 13c of the longer limb 13a, but the action of the plate 7 on the free edge 13d of the shorter limb 13b is to bend this first inwardly and then parallel to the said longer limb so as to produce a longitudinal flange 13e. The upper edge portions of the limbs 13a and 13b then pass between the opposed die plates 8 and 9. As shown more clearly in Figures 5 and 7, the upper portion of the operative end of the plate 8 is formed with a suitably curved lateral projection 8a, whilst the top surface of the operative end portion of the opposed plate 9 is so rabbeted as depicted in Figures 4 and 10, as to provide thereon a flange 9a having a curved leading end and the underside of which is flush with the bottom of the last mentioned plate. The action of the lateral projection 8a on the projecting edge 13c of the longer limb 13a is to bend this edge down flat onto the flange 9a so that it extends laterally inwards and assumes a horizontal disposition as illustrated in Figure 10. Next, the edges of the limbs 13a and 13b pass between the opposed die plates 10 and 11. The operative end of the plate 10, like that of the plate 6, is flat and vertically disposed (Figures 4 and 5), but the opposed end portion of the plate 11 is so contoured and rabbeted on its underside, as shown more clearly in Figure 6, as to provide thereon an overhanging lip 11a adapted to act on the projecting edge 13c of the longer limb 13a and bend this edge vertically downwards so that it embraces the aforementioned longitudinal flange 13e and produces a tube-closing seam 13f (see Figure 11). Finally, the interengaged portions of the limbs 13a and 13b constituting the side seam, as they travel forwardly beneath a curved and laterally extending formation 12a (see Figure 8) on the operative end of the last die plate 12, are bent over at right angles so as to lie against the adjacent narrow side of the flat section 15 of the lock seamed tubing T thus produced (see Figure 12). It will be noted that the die plate 12 is a single one and not one of a pair.

As will be appreciated from Figures 1A and 4, each of the die plates 6—12 has formed therein a hole 18 to

enable it to be engaged over the appropriate one of a series of screwed locating studs 19 extending vertically upwards from the top surface of the relevant one of the two opposed die blocks 3 and 4. The said plates are clamped in position on the tops of the blocks by means of nuts 20 screwed onto the upwardly projecting portions of the studs 19.

Arranged to extend right through the channel 5 in the die unit 2 is a flat section bar 21 constituting a mandrel about which the tubing T is formed. The tail end of the mandrel 21 is connected by means of suitable linkage with a lever 22 whereby the mandrel can be withdrawn from and projected into the unit 2 as occasion may demand. The lever 22 is secured upon a spindle 23 arranged to turn in plates 24 attached to the outsides of the blocks 3 and 4. A screw having a knurled head 25 is provided for locking the mandrel in its operative position. Preparatory to starting up the machine, the leading end of the strip metal can be pushed through the die unit 2 with the aid of the mandrel 21.

For gripping and feeding forwards the finished tubing T emerging from the die unit 2, and thereby continuously drawing the strip metal through the die head A, there is provided in this particular example a pair of feed wheels 26 and 27 (Figures 1 and 1A). These wheels, which are horizontally disposed and arranged to revolve about vertical axes, are located between a base plate 28 and the superimposed horizontal member 29 of a bridge structure 30. It is convenient here to mention that the mandrel 21 is sufficiently long to extend between the feed wheels 26 and 27 for the purpose of preventing the grip exerted by the latter from crushing the tubing. The bearings for the spindle of the feed wheel 26 are fixed and this wheel is adapted to be continuously driven, e.g. from an electric motor through the medium of reduction gearing. The feed wheel 27, on the other hand, is driven from the companion wheel 26 for which purpose the wheels are integrally combined with intermeshing spur gears 31 and 32. Moreover, to enable the feed wheels to grip the tubing T yieldingly between them the spindle of the feed wheel 27 is mounted to rotate in spring-influenced bearing blocks 33 (Figure 1) which are slidable in transverse slots 34 and 35 formed in the base plate 28 and the superimposed member 29 respectively. Compression springs 36 are accommodated within the slots 34 and 35 for action upon the slidable bearing blocks 33, and manually operable screws 37 are provided for adjusting the spring pressure, according to requirements. The reference numeral 38 indicates oiling nipples. The feed wheels 26 and 27 are peripherally recessed at 39 to receive and engage the respectively opposite sides of the lock seamed tubing T, and the bottoms or backs of the recesses are knurled at 40 to enhance the grip of the wheels on the tubing. As it issues from the nip of the feed wheels 26 and 27 the tubing passes between pairs of conventional straightening rolls such as 41 and 42 the inner faces of which are circumferentially rabbeted in known manner for engagement with the outerside of the tubing. There are two spaced pairs of the rolls 41 and an intermediate single pair of rolls 42 mounted on manually adjustable eccentrics. In Figure 1 only one of the pairs of rolls 41 is shown, the other pair being hidden by the feed wheel 27 and the bridge structure 30.

Located between the die unit 2 and the feed wheels 26 and 27, as illustrated in Figures 2 and 3, is a pair of superimposed rollers 43 and 44 adapted, by engagement with the narrow sides of the tubing T, to squeeze the latter to correct size widthwise by flattening the tube-closing seam 13f. Of these two rollers the bottom or bed roller 43 is disposed in a vertical space between the rear ends of the two die blocks 3 and 4 and is provided with an axle 45 the opposite ends of which are located in co-axial holes 46 formed in the said blocks as shown in Figure 3. The top roller 44, on the other hand, is

arranged to revolve within a vertical recess 47 formed in a block 48 disposed above and transversely across the rear ends of the die blocks 3 and 4. The block 48 is drilled right through to provide a hole 49 for reception of the axle 50 of the roller 44. Ball bearings may advantageously be provided between the axles 45 and 50 and the rollers 43 and 44 respectively. The block 48 is also vertically drilled for engagement with and to enable it to slide up and down along two parallel spaced vertical slide rods 51 the lower ends of which are set in the die blocks 3 and 4. The bottom ends of the vertical holes drilled in the block 48 are counterbored to receive compression springs 52 which surround the slide rods 51 and are interposed between the blocks 3 and 4 and the superimposed block 48. The tops of the rear ends of the blocks 3 and 4 are slightly recessed to enable the top roller 44 to engage and press down on the longitudinal seam 13f. For depressing the block 48 against the action of the compression springs 52 and so causing the roller 44 to engage the tubing, under the required degree of pressure, there is provided a vertically disposed adjustable screw 53 the leading, i.e. lower, end of which is turned down into the form of a plunger 54 adapted to fit within and to act on the bottom of a hole 55 formed in the top of the said block. The screw 53 is engaged in a tapped hole formed in a fixed cross member 56 carried by and at the upper ends of the slide rods 51. In this connection the upper end portions of the said slide rods are reduced in diameter and screw-threaded at 51a to receive nuts 57 whereby the cross member 56 is secured in position. Lock nuts 58 and 59 are provided for locking the screw 53 after an adjustment thereof.

The machine may also, if desired, include a parting-off saw operable for automatically sawing off the finished tubing tubes of any desired length while the machine is in operation.

The strip metal may be continuously drawn from a coil of the material in which instance the machine may incorporate a coil holder and an associated tensioner.

The machine of this invention may, moreover, embody flux, solder or other tanks by which the strip metal can be tinned or soldered either before or after the tube drawing operation.

The machine may include a sheet metal cabinet upon the top of which are mounted the die head and the feed wheels; within the cabinet would be accommodated the coil holder and tensioner, the driving means for the feed wheels, and the flux, solder or other tanks.

I claim:

1. A tube drawing machine for continuously producing quadrangularly-sectioned lock-seamed tubing from an initially flat strip comprising, in combination, a U-shaped trough for initially folding the metal strip into a U-formation with one leg of the U slightly longer than the other leg, a guide channel through which the U-formation can be drawn, said channel being of such depth that a portion of both legs extends above said channel, a series of die heads overlying said channel, the die heads comprising means for bending the free edge of the shorter leg both inwards and upwards parallel to the longer leg to form an L-shaped flange, means for bending the free edge of the longer leg laterally inwards and then downwards to overlap the upper and projecting edge of said first named leg, and further means bending the inner engaged portions of both legs over the lie adjacent to the horizontal portion of said shorter leg, a pair of superimposed sizing rollers having horizontal axes and adapted to press upon the upper

and lower sides of the tubing to compress the closing seam and thus accurately size the tubing, a pair of knurled feed wheels rotatable about vertical axes between the nip of which the tubing passes, means for driving the wheels, said 5 wheels gripping the vertical sides of the tubing and feeding forwards the finished tubing emerging from the sizing rollers thereby continuously drawing the metal strip through the latter, and a mandrel of uniform cross-section extending through the channel and between the feed 10 wheels about which the tubing is formed, said mandrel being rigidly held by linkage means attached at the entrance to said channel.

2. A tube drawing machine according to claim 1, where-in said die means include a first pair of die plates the operative end of one is wholly flat and disposed in a vertical plane whereas the opposed end of the other is curved and formed at one of the top corners thereof with a laterally protruding lip, the end of the first mentioned plate having no appreciable effect on an upwardly projecting edge portion of a longer limb of an initially folded strip, but the opposed end of the second mentioned plate being adapted, by action on the free edge of the shorter limb of the folded strip, to bend this edge first inwards and then parallel to the said longer limb.

25 3. A tube drawing machine according to claim 2, where-in the upper portion of the operative end of one of the second pair of die plates is formed with a curved lateral projection whilst the top surface of the operative end portion of the opposed die plate is so rabbeted as to provide 30 thereon a flange having a curved leading end the underside of which is flush with the bottom of the last mentioned plate, the action of the aforesaid lateral projection on the projecting edge of the longer limb of the folded strip being to bend this edge down onto the flange so 35 that the said edge extends laterally inwards.

4. A tube drawing machine according to claim 3, where-in the operative end of one of the third pair of die plates is flat and vertically disposed, whereas the opposed end portion of the other plate of the pair is so contoured and 40 rabbeted on its underside as to provide thereon an overhanging lip adapted to act on the projecting edge of the longer limb of the folded strip and bend this edge vertically downwards so that it embraces a previously formed flange on the shorter limb to produce a tube-closing seam.

45 5. A tube drawing machine according to claim 4, where-in a single die plate following the third pair of opposed die plates has a curved and laterally extending formation on its operative end, this formation being adapted, by action on the interengaged portions of the limbs constituting the tube-closing seam, to bend these portions 50 over so that they lie against the adjacent narrow side of the lock seamed tubing.
